J. L. Lay,
 Compound Steam Engine.
 N° 66,975. Patented July 23, 1867.

Fig. 2

United States Patent Office.

JOHN L. LAY, OF BUFFALO, NEW YORK, ASSIGNOR TO HIMSELF AND
H. O. PERRY, OF SAME PLACE.

Letters Patent No. 60,975, dated July 23, 1867.

IMPROVEMENT IN STEAM ENGINES.

The Schedule referred to in these Letters Patent and making part of the same.

TO ALL WHOM IT MAY CONCERN:

Be it known that I, JOHN L. LAY, of the city of Buffalo, in the county of Erie, and State of New York, have invented certain new and useful Improvements in Vertical Compound Engines; and I do hereby declare, that the following is a full and exact description thereof, reference being had to the accompanying drawings, making part of this specification, in which—

Figure 1 is a central vertical section of my improved engine.

Figure 2 is a front elevation of the same with portions of the valve-chest broken away to show the ports.

Figure 3 is a view, partly in section, of the valve detached.

Like letters designate corresponding parts in all the figures.

The design of my invention is the production of a compound engine, consisting of a high and a low-pressure cylinder, of a compact form, suitable for vessels propelled by means of a screw.

The invention consists in the special arrangement of the cylinders concentrically, one within the other, with their pistons connected by three rods attached to a common cross-head below the cylinders; and also in the construction and arrangement of a single oscillating valve for operating both cylinders, all as hereinafter fully set forth.

In the drawings, A B represent two cylinders, the latter arranged concentrically within the former, and both closed at their ends by the same heads C D. E is the piston of the inner, and F the annular piston of the outer cylinder, the former attached to the ends of a rod, G, and the latter to two rods, H I, all extending downward through the bottom head D, where they are fastened to the same cross-head J, as represented. From this cross-head a rod connects with the crank of the screw-shaft. The steam from the boiler enters the smaller or high-pressure cylinder, and is cut off at any desired point, effecting a certain amount of expansion in that cylinder, from whence it is exhausted into the larger cylinder and expands the whole length of the stroke, and thereby is expanded in both cylinders.

The advantages of this arrangement of the cylinders are: Great compactness and power, as they together occupy no more space than a single one would, while their combined power is much greater. It also brings the centre of gravity of the engine and connecting machinery much lower than it would be were they arranged one above the other. It is more simple, cheaper, and weighs less than any other arrangement of the same power with which I am acquainted.

K represents the valve-chest; L an oscillating valve, and *m n o p* the ports, of which *m n* are the steam-ports to the high-pressure, and *o p* the ports to the low-pressure cylinder; and *g* is the exhaust-chamber, which opens into the valve-chamber *r*, from whence the exhaust steam escapes through the trunnion *s* into the external air or condenser, as required. The port *m* opens into the top of the high-pressure cylinder through the head, *C*, while the port *n* communicates in like manner, as shown, with the bottom of same. The port *o* leads to the top of the low-pressure cylinder *A*, opening into the same through the side, while *p* connects in like manner with the bottom of the cylinder, the former connecting with the port *n* and the latter with *m*, while the valve is respectively at its extreme throws, when they operate as an exhaust from the high-pressure cylinder and conduct the steam to the lower-pressure cylinder. The steam exhausts from the cylinder *A* alternately through the ports *o p* into the chamber *g*, whence it escapes through the valves, as before described. The valve *L* terminates at the end in a hollow trunnion, *s*, and at the other in a spindle, *t*, by which it is connected to the eccentric that gives it the required oscillating motion. The face of the valve forms an arc, with the axis at its centre, with which the valve-seat corresponds. It is provided with two cavities, *u u*, and a recess, *v*, at the centre, leading into the valve-chamber *r*. The face of the valve alternately covers *m* and *n* at the extreme throws; the valve being represented in fig. 1 as closing port *m*, while steam is admitted through *n* to the bottom of cylinder *B*, and at the same time exhausted from the upper end of the same through port *m*, which now communicates with the port *p* that conducts the exhaust steam to the lower end of the low-pressure cylinder *A*, (as shown by the arrows,) port *o* connecting with the upper end of the cylinder *A*, affording a passage for the exhausted steam therefrom into the chamber *g*, into which it now opens; from thence it escapes through recess *v* into the valve-chamber *r*, and thence through the trunnion, as above described. When the valve is at the other extreme

it is evident that the port *n* will be closed and *m* opened, causing simply a reverse movement of the steam through the various ports, the port *p* now opening into the chamber *g* instead of the port *o*.

The advantages of this part of my invention are, first, dispensing with the use of one or more valves and the necessary machinery required for operating them, as my simple valve performs the functions of two or more as they are ordinarily constructed; second, the great saving in expense and in the space required for the valve and actuating machinery, as well as for the engine itself; third, the diminished weight of the same, which, on the vessels for which this engine is designed, is of considerable importance.

1. I claim the arrangement of the high-pressure cylinder *B* concentrically within the low-pressure cylinder *A*, when both are closed by the same heads *C D*, and the pistons actuate rods attached to the same cross-head below the cylinders.

2. I also claim the valve *L* provided with the cavities *u u*, recess *v*, valve-chamber *r*, and hollow trunnion *s*, in combination with the ports *m n o p* and chamber *g*, for operating the two cylinders of a high and low-pressure engine, substantially as set forth.

3. The valve, constructed as described, in combination with the concentric cylinders *A* and *B* of a high or low-pressure engine.

In witness whereof I have hereunto signed my name in the presence of two subscribing witnesses.

JOHN L. LAY.
